DISPLAY RACK

Harry C. Robinson, Chattanooga, Tenn.

Application December 11, 1936, Serial No. 115,423

6 Claims. (Cl. 211—181)

This invention relates to racks or stands broadly and particularly to display racks of the wire frame type designed to be folded or collapsed for shipment or storage. Racks of the foregoing type are made in varying sizes and are oftentimes called upon to support relatively large quantities of and/or heavy merchandise, and it is highly desirable that they be capable of carrying such merchandise without danger of giving way or of swaying and bending, while at the same time the rack should be capable of low cost manufacture, light in weight and foldable into a compact bundle for shipment or storage.

The present invention, therefore, includes among its objects: to provide a wire rack or display stand which is strong and sturdy and is braced against both vertical and lateral stresses or strains that may be imposed thereon in supporting relatively heavy quantities of merchandise; is foldable or collapsible into a compact bundle; is capable of being made at practically any desired height and with any desired number of trays without danger of sagging or becoming rickety; and is designed for ease and economy in manufacture and particularly for manufacture by the electric welding process.

The foregoing and other objects and advantages will become apparent in view of the following description taken in conjunction with the drawing, wherein:

Figure 1 is a view in perspective of a rack embodying the features of the present invention;

Figure 2 is a view in transverse vertical section of the rack of Figure 1;

Figures 3 and 4 are views similar to Figure 2 with the rack partially and completely folded, respectively;

Figure 5 is a view taken substantially on the line 5—5 of Figure 4;

Figure 6 is a fragmentary view of the upper portion of a rack showing a modified type of tray lock.

The main supporting frame comprises a pair of legs made up of a substantially U-shaped wire 5 and a substantially rectangular shaped wire 6, the wire 5 having its free ends bent around the wire 6 as at 7 to thereby provide a hinge connection at the upper end of the frame members. When these frame or leg members 5 and 6 are opened out they define an inverted V. These leg-frame members may be made of any desired height in accordance with the desired carrying capacity of the rack, and the particular shape thereof varied to meet varying conditions of use. Thus the base of the frame may be

shaped to provide individual legs contacting the floor or ground at four spaced points to better conform to uneven floors; the frames may be reinforced by cross members, and other changes in shape and structure adopted to meet conditions, the invention not being particularly concerned with this part of the rack.

Connected at their opposite ends to the side uprights of the leg frames 5 and 6, preferably by electric welding, are a plurality of transverse tray supporting bars or wires 8, 9, 10 and 11, these bars being designed to support trays generally indicated at 12 and 13. The central portions of the trays 12 and 13 are preferably made up of a plurality of reinforcing and supporting wire or rod members 12a and 13a, said latter members having their opposite ends connected to the outer frame structure preferably also by electric welding. The trays 12 and 13 are preferably hinged to the cross bars 8 and 9 respectively by means of loops or bands 14 and 14a, which pass beneath the supporting bars 8 and 9, in conjunction with the tray bars 12a and 13a, which pass over said wires.

It will be understood that there may be as many cross rods 8, 9, 10 and 11 and trays 12 and 13 as may be desired in accordance with the height of the rack and the required capacity thereof, and these trays may be provided with various types of holding or retaining members to accommodate the particular type of merchandise carried thereby.

The upper rack 13 is provided with catches or locks 15, which are preferably of L-shape with the open end of the catch facing inwardly of the rack, while the lower tray 12 is provided with catches or locks 16 which are preferably of inverted U-shape with the open ends facing downwardly when the rack is unfolded. Each of these catches or locks 15 and 16 is preferably formed of a single piece or short length of wire which is bent into shape and electrically welded to the outer frame member of the tray, although it could obviously be connected to any of the central cross rods which make up the body of the tray. It will be noted that when the rack is unfolded, the upper L-shaped catch or lock 15 engages the cross bar 10 and limits and at the same time determines the unfolded position or spread of the leg frame members 5 and 6, and at the same time locks the tray 13 in horizontal position and prevents tilting or overbalancing of the tray when the same is loaded or overweighted exteriorly of the leg frame, and when this limit is reached, the inverted U-shape 55

catches or locks 16 are in a position to register with the supporting cross bar 11. This co-operating L- and U-shape combination of catches or locks not only facilitates the unfolding and proper placement of the rack but also ensures a rigid structure which is braced against lateral or twisting strains or stresses, while at the same time the cross bars 8, 9, 10 and 11 form a rigid brace against the vertical load imposed on the 10 trays. As an additional strengthening operation, the ends of the wires which form the outer frame of the trays 12 and 13 are joined at the point where the catches 15 and 16 are welded thereto. By this means, also, the said ends are united 15 and the catches attached by a single welding operation.

In collapsing or folding the rack, bottom tray 12 is first swung upwardly in substantial alignment with the side member of frame 5. This operation frees the catches 16 from the supporting rod 11, whereupon the leg frame members 5 and 6 may be moved together until the catches 15 are free from the supporting rod 10. The leg frames 5 and 6 may then be spread apart, and as soon as 25 the rod 10 clears the end of tray 13, the latter swings downwardly also in substantially parallel relation with the side members of the leg frame 6 against the upper portion of the tray 12. The leg frames 5 and 6 may then be collapsed, where- 30 upon the rack is compactly folded as illustrated in Figures 4 and 5.

Practical experience has demonstrated that the foregoing construction provides a rack which has the desirable characteristics heretofore enumerated. 35

In Figure 6, another type of lock for the supporting frames is illustrated which may be used in place of the locks 16, or if desired, in conjunction with the latter. In this instance one or 40 more latch locks 18 are pivoted or hinged on the tray 13 and have hooked ends adapted to engage one of the cross bars 9 or 10, the lock shown engaging bar 10. By this means the supporting frames 5 and 6 are locked against inward movement while at the same time the locks 15 hold 45 said frames against spread or outward movement.

It will be understood that other changes in structure and design may be adopted within the scope of the invention as defined by the appended 50 claims.

I claim:

1. A rack for display and like purposes comprising a pair of hinged wire leg frames which when unfolded define an inverted substantially 55 V-shaped supporting structure, tray supporting and leg reinforcing cross bars connected at their opposite ends to the upright wire legs at the sides of each leg frame and arranged in substantial alignment transversely of the rack, 60 foldable wire trays having hinged connection with the cross bars of one leg frame and spanning the space between the frames when the latter are spread apart and adapted to rest on the aligned cross bar of the other leg frame, and 65 catch members connected to said trays adapted to engage the said last-named bars and hold the trays and legs in set-up position, the catches of one of said trays being arranged to engage its coacting bar substantially horizontally and those 70 of another of said trays being arranged to engage its coacting bar substantially vertically to thereby coat to brace the rack against both vertical and lateral stresses.

2. A rack for supporting articles of merchandise and the like comprising a pair of hinged wire 75

leg frames which when unfolded define an inverted substantially V-shaped supporting structure, tray-supporting and leg-reinforcing cross bars connected at their opposite ends to the upright wires at each side of said leg frames and arranged in substantial alignment transversely of the rack, foldable wire trays each having a hinge connection with a cross bar of one leg frame and spanning the space between the frames when the latter are spread apart and 10 adapted to rest on the aligned cross bar of the other leg frame, and latch members connected to said trays and adapted to engage said latter bars for holding the trays and legs in set-up position, the latch members of one of said trays 15 being of substantially L-shaped contour and disposed horizontally and the lock or latch members of another of said trays being of substantially inverted U-shaped contour and disposed vertically of the tray when the latter is unfolded. 20

3. A display rack comprising a pair of hinged wire leg frames, one of which is of substantially rectangular shape and the other of which is substantially U-shaped with its free ends bent around and connected to said rectangular leg 25 frame to provide a hinge connection, the leg frames when unfolded defining an inverted V-shaped supporting structure, cross bars each connected at their opposite ends to the upright wires of a leg frame, said cross bars being arranged in horizontally aligned pairs transversely of the rack, foldable wire trays hinged at one side to the cross bars of one leg frame and adapted to span the space between said frames and rest on the aligned cross bars of the other frame, one of 30 said trays being provided with L-shaped catches which are disposed transversely of the rack and are adapted to engage the cross bar on which it rests and limit the opening or spreading movement of the legs, the other of said trays being provided with substantially inverted U-shaped catches which are adapted to register with a cross bar when the legs reach the extreme spread or unfolded position determined by said L-shaped catches. 45

4. A display rack comprising a pair of wire leg frames one of which is substantially rectangular and the other of which is of substantially U-shape with its upper free ends bent around the upper end of the rectangular frame to provide 50 a hinged connection therewith, said leg frames when unfolded defining an inverted substantially V-shaped supporting structure, cross bars secured at their opposite ends to the upright side legs of each leg frame and arranged in aligned 55 pairs transversely of the rack, upper and lower foldable wire trays each pivotally connected to a cross bar of one leg frame and adapted to rest on the aligned cross bar of the other frame when the rack is in set-up position, the upper tray being provided with substantially L-shaped catch members which lie in a substantially horizontal plane when the tray is in set-up position and are adapted to engage said aligned cross bar and limit the opening or spreading movement of the 60 leg frames, the lowermost tray having connected thereto one or more substantially inverted U-shaped catches adapted to register with the cross bar opposite that to which said lower tray is pivoted when the legs are spread to the point 65 determined by said first named catches. 70

5. A rack for display and like purposes comprising a pair of pivotally connected wire leg frames which when unfolded define an inverted substantially V-shaped supporting structure, tray 75

- supporting and leg reinforcing cross bars connected at their opposite ends to the upright wire legs and arranged in substantial alignment transversely of the rack, a plurality of trays 5 pivotally supported from the cross bars of one leg frame so as to swing into a plane substantially parallel to said latter frame when the rack is folded and to swing outwardly and be supported by the aligned cross bars of the other leg frame 10 when the rack is unfolded, at least one of said trays extending laterally beyond its supporting cross bars and being provided with catch means adapted to detachably engage the adjacent rack structure when the rack is unfolded and prevent 15 tilting of the tray and also brace the leg frames against spreading movement.
6. A rack for display and like purposes comprising a pair of pivotally connected wire leg frames which when unfolded define an inverted 20 substantially V-shaped supporting structure, tray

supporting and leg reinforcing cross bars connected at their opposite ends to the upright wire legs and arranged in substantial alignment transversely of the rack, a plurality of trays pivotally supported from the cross bars of one leg frame so as to swing into a plane substantially parallel to said latter frame when the rack is folded and to swing outwardly and overlie and be supported by the aligned cross bars of the other leg frame when the rack is unfolded, one of said 10 trays being provided with a catch member constructed to engage the adjacent rack structure when the rack is unfolded and lock the tray against tilting movement and also limit the spread of the leg frames and another of said trays being 15 provided with a catch member constructed to engage the adjacent rack structure and hold the leg frames against inward movement.
